SAUNA STOVE

Henry P. Glass, Chicago, Ill., assignor to Welded Products, Inc., Grand Haven, Mich., a corporation of Michigan

Filed Aug. 2, 1963, Ser. No. 76,086

Term of patent 14 years

(Cl. D81—20)

FIG. 1.

FIG. 2.

FIG. 3.

FIG. 1 is a side elevation of a sauna stove showing my new design;

FIG. 2 is a top plan view thereof with the stones shown in broken lines for illustrative purposes; and

FIG. 3 is a perspective view thereof.

The dominant features of my design reside in the portions shown in full lines.

I claim:

The ornamental design for a sauna stove, substantially as shown and described.
